(57) **CLAIM**

The ornamental design for a dual mount, angle adjustable tool holder for extension poles, as shown and described.

DESCRIPTION

FIG. 1 is a front perspective view of a dual mount, angle adjustable tool holder for extension poles showing my new design.

FIG. 2 is a side elevational view thereof;

FIG. 3 is a side elevational view taken from the left in FIG. 2.

FIG. 4 is a rear elevational view taken from the left of FIG. 3;

FIG. 5 is an opposite side elevational view taken from the left of FIG. 4;

FIG. 6 is a top plan view taken from the top in FIG. 4; and,
FIG. 7 is a bottom plan view taken from the bottom in FIG. 2.
